COMBINED RACKET COVER AND PRESS

Christopher T. Rood, 3561 Bayard Drive, Cincinnati,
Ohio 45208, and Howard H. McIlvain, Cincinnati,
Ohio; said McIlvain assignor to said Rood

Filed Oct. 24, 1974, Ser. No. 517,583

Term of patent 14 years

Int. Cl. D21—02

U.S. Cl. D34—5 ST

FIG. 1 is a perspective view of the top and sides of a combined tennis racket press and cover showing our new design;

FIG. 2 is a perspective view of the bottom and sides;

FIG. 3 is a top view thereof;

FIG. 4 is a bottom view thereof;

FIG. 5 is a side view thereof;

FIG. 6 is an end view thereof showing the racket handle-receiving opening;

FIG. 7 is a view of the end opposite to that shown in FIG. 6.

We claim:

The ornamental design for a combined racket cover and press, as shown.
